Primary Examiner — Mitchell I. Siegel*(74) Attorney, Agent, or Firm* — Cozen O'Connor(57) **CLAIM**

The ornamental design for a domed golf ball marker, as shown and described.

DESCRIPTION

FIG. 1 is a perspective view of a domed golf ball marker in accordance with the new design;

FIG. 2 is an exploded bottom perspective view thereof;

FIG. 3 is a top plan view thereof;

FIG. 4 is a bottom plan view thereof;

FIG. 5 is a front elevational view thereof; and,

FIG. 6 is a side elevational view thereof.

The broken lines in FIGS. 1-6 illustrate portions of the domed golf ball marker that form no part of the claimed design.
